UNITED STATES PATENT OFFICE.

HANS J. HANSON, OF LITCHVILLE, NORTH DAKOTA.

MAIL-BOX SUPPORT.

949,231.

Specification of Letters Patent. Patented Feb. 15, 1910.

Application filed May 17, 1909. Serial No. 496,554.

To all whom it may concern:

Be it known that I, HANS J. HANSON, a citizen of the United States, residing at Litchville, in the county of Barnes and State 5 of North Dakota, have invented certain new and useful Improvements in Mail-Box Supports, of which the following is a specification.

My invention relates to improvements in 10 mail box supports, and the leading object of my invention is the provision of a simple, cheap and durable device for supporting mail boxes which will retain the box firmly in position and may be adjusted to fit any 15 box.

Another object of my invention is the provision of a device of this character which can be readily applied to the box and which 20 is capable of vertical adjustment to correspond to the desires of the carrier.

With these and other objects in view, my invention consists in the novel features of construction and combination and arrangement of parts substantially as disclosed 25 herein and as illustrated in the accompanying drawings.

Figure 1, represents a plan view of my support with a box in position, part of the post being shown in section. Fig. 2, represents an end plan view of the support with 30 a box applied in position, and, Fig. 3, represents a perspective view of the adjustable portion of the support and the box grasping means.

35 In the drawings: the numeral 1, designates a tubular vertical post having the lower end set in the ground, and in its upper open end is inserted the angular tube 2, of sufficiently small diameter to move freely in the inside of the tube 1, and to limit said sliding motion, I provide the screw 3, having its shank engaged in a threaded socket 4 in the post 1, said screw being adapted when turned to move inward 40 in the socket and have its end engage the tube 2 and hold it in adjusted position.

The tube 2 consists of the upright leg 5 fitting in the post 1, and the leg 6 bent at right angles thereto, and said leg 6 is provided 45 with openings in its sides through which are passed the threaded ends of the angular hooks or clamping members 7, said hooks being held in place by means of the nuts 8, which engage the threaded ends thereof.

The clamping members 7, consist of a

horizontal portion having a threaded end and an upright portion for engaging the mail box, and said upright portion may be straight or the upper end thereof may be 60 bent inward to form a hook on the end thereof.

In operation, I first firmly set the post 1, in the ground, and then insert the tube 2 in the upper end thereof and after setting 65 it down till the leg 6 is at the desired height, I tighten the screw 3 till it engages the tube and holds it securely in position. I then set a mail box on the leg 6 and turn the hooks 7 till their upright portions are in a 70 vertical plane and then by turning the nuts 8 I force them into firm engagement with the sides of the box, thus locking it securely in place.

It will be understood that my device will 75 hold any box having vertical side walls securely in position, but to insure the best results I preferably provide the box with recesses in its sides in which the clamping members will engage, and with this species 80 of box I also bend the upper ends of the hooks inward to still more firmly engage and hold the box.

From the foregoing description taken in connection with the drawings the operation 85 and advantages of my device will be readily understood, and it will be seen that I provide a mail box support of simple, cheap and durable construction which can be adjusted to fit any ordinary box, and which can be 90 vertically adjusted to satisfy the users thereof.

It will be understood that while the support is particularly adapted for use in rural delivery, it may be used for any purpose 95 where it would perform the desired function.

I claim:

1. A mail box support, comprising a tubular post, an angular rod mounted therein, means for adjustably securing the rod in 100 the post, and alternately disposed clamps secured to the outer end of the rod for securing the mail box thereon.

2. In a device of the character described, the combination with a supporting rod having a horizontally disposed arm with passages formed therein, of clamps passing through said passages and having their clamping ends alternately projecting from the arm on opposite sides thereof.

3. In a device of the character described, the combination of an angular adjustable

support, and clamps removably and adjustably secured to the end of the support and projecting alternately from opposite sides thereof.

5. 4. In a device of the character described, the combination with a tubular post, of a vertically adjustable angular rod secured therein, clamps passing through the outer end of the rod, and means engaging the free ends of the clamps and bearing against the rod for securing the clamps in engagement with the sides of the mail box.

10 5. In a device of the character described, the combination of a tubular post, an angu-

lar support adjustably secured therein having a series of openings formed in its outer end, clamps having screw threaded ends passed through said openings from alternate sides of the rod, and means engaging said threaded ends and bearing against the support for forcing the clamps into engagement with the sides of the mail box.

15 20 In testimony whereof I affix my signature, in presence of two witnesses.

HANS J. HANSON.
